UNITED STATES PATENT OFFICE.

RICHARD A. WHALL, OF READING, MASSACHUSETTS, ASSIGNOR OF ONE-HALF TO METROPOLITAN AIR GOODS COMPANY, OF READING, MASSACHUSETTS, A CORPORATION OF MASSACHUSETTS.

HOT-WATER BAG OR BOTTLE.

No. 858,550.

Specification of Letters Patent.

Patented July 2, 1907.

Application filed April 21, 1906. Serial No. 313,016.

To all whom it may concern:

Be it known that I, RICHARD A. WHALL, of Reading, in the county of Middlesex and State of Massachusetts, have invented certain new and useful Improvements in Hot-Water Bags or Bottles, of which the following is a specification.

This invention has for its object to provide a simple and inexpensive construction for hot water bags, whereby a bag may be produced at a minimum expense, and of great durability and freedom from liability to leakage.

The invention also has for its object to provide improved means for protecting the user of the bag against injury from the heated surface, by providing the bag with a covering of fibrous material, such as felt, provided with perforations which permit the outward radiation of heat from the bag, the portions of the felt surrounding the perforations preventing direct contact between the heated rubber surface of the bag and the skin of the user.

The invention consists in the improvements which I will now proceed to describe and claim.

Of the accompanying drawings, forming a part of this specification,—Figure 1 represents a side elevation of a water bag embodying my invention. Fig. 2 represents a section on line 2—2 of Fig. 1. Figs. 3 and 4 represent fragmentary sectional views showing different stages of the operation of making my improved bag.

The same letters of reference indicate the same parts in all the figures.

In the drawings, *a a* represent two pieces which constitute the major portion of a hot water bag, the said pieces being formed from frictioned fabric, coated on both sides with unvulcanized rubber, and having their marginal portions placed together side by side, to form a joint. Said marginal portions are united by fastening devices which are preferably stitches *b* extending parallel with the edges of the side pieces to positively maintain the joint. This operation is performed before the vulcanizing operation, the frictioning material of the side pieces being unvulcanized.

c represents a packing strip, which is V-shaped in cross section, and is in contact with the portions of the inner sides of the side pieces *c* which are adjacent to the joint, said packing strip being interposed between the joint and the interior of the bag, and excluding liquid from the fastening devices. The packing strip *c* is composed of, or treated with, rubber prepared for vulcanization. The apex of its V-shaped cross section is in close proximity to the stitches *b*, the side portions diverging from the apex, and being in close contact with

the side pieces *a a*, the arrangement being such that the pressure of water contained in the bag tends to press the packing strip outwardly against the inner sides of the side pieces *a a*, thus preventing the contents of the bottle from flowing outwardly to the stitches *b*.

d represents a binding strip composed of suitable fabric, which is internally frictioned, this strip being folded over the edges of the side pieces *c c*, and caused to overlap and cover the stitches *b*, as shown in Fig. 2.

The above-described parts are assembled in the manner shown, prior to the vulcanizing operation, which operation causes the permanent adhesion of the packing strip *c* and binding strip *d* to the side pieces *a a*.

It will be seen that the above-described construction is extremely simple, as well as durable, and free from liability to leakage. The fastening devices positively connect the margins of the side pieces, making the joint permanent, while the packing strip prevents the entrance of liquid into the joint, and its access to the fastening devices.

f represents a protective covering of fibrous material applied to the external surface of the bag, the said covering being composed of felt or other suitable fibrous material which has less heat conductivity than rubber. The covering *f* is provided with numerous perforations *f'* which expose small areas of the rubber, and are so numerous that they expose considerable areas of heat radiating surface. The exposed areas are protected by the imperforate portions of the felt, the perforations being so small that the exposed portions of the rubber cannot come in contact with the user's skin. The perforations form heat-conducting passages extending outwardly from the sides of the bag, thus facilitating the radiation of heat from the bag. I have shown the protective covering only in Fig. 2.

I claim:

1. A water bag comprising side pieces, placed in contact with each other side by side, and stitched together at their margins, a V-shaped packing strip secured to the inner sides of the side pieces and extending parallel with the line of stitches, and an internally frictioned binding strip folded over the edges of the pieces and covering the said stitches, the said parts being united by vulcanization.

2. A water bag having heat radiating outer surfaces and protecting coverings therefor, composed of perforated sheets of fibrous material, the perforations in said sheets exposing portions of the heat radiating surfaces of the bag, and forming unobstructed heat-conducting passages.

In testimony whereof I have affixed my signature in presence of two witnesses.

RICHARD A. WHALL.
